HELMET

John M. Egly, Tonawanda, N. Y., assignor to the United States of America as represented by the Secretary of the Army

Application December 27, 1957, Serial No. 49,044

Term of patent 14 years

(Cl. D3—13)

I claim:

The ornamental design for a helmet, substantially as shown.
